UNITED STATES PATENT OFFICE

AUBREY H. TABOR, OF LAEGER, WEST VIRGINIA

SIGN HOLDER

Application filed May 31, 1930. Serial No. 458,502.

This invention relates to a new and improved sign holder especially, but not necessarily, adapted for use on railway cars and the like for holding various types of indicia 5 equipped cards in display position.

In carrying the conception into practice, I have evolved and produced a simple and economical device of this class characterized by an especially designed fixedly mounted 10 frame, and a practicable form of resilient card retainer, attached thereto in a position to permit the card or cards to be firmly clamped between the frame and the retainer.

The specific details and the relative arrangement and association thereof, will become more readily apparent from the following description and drawings.

In the drawings:—

Figure 1 is an elevational view of a device 20 constructed in accordance with the present invention.

Fig. 2 is an enlarged vertical sectional view on the line 2—2 of Fig. 1.

Fig. 3 is a view like Fig. 2, showing the resilient retainer swung inwardly against the car body to an out-of-the-way temporary position to facilitate application and removal of the card.

Fig. 4 is a perspective view of the especially fashioned retainer.

In Fig. 1 the reference character 5 designates the frame. This is generally rectangular in configuration, and includes spaced parallel side walls 6 provided with 35 apertured attaching ears 7 to permit the frame to be securely fastened to the body 8 of the car. The lower end portions of these side walls 6 are formed with inwardly pressed 40 projections 9 constituting keepers for holding the retainer in the position represented in Fig. 3.

The frame is of open-work design and embodies upper and lower bar members 11 and 12 and a pair of intermediate bar members 45 13 and 14 defining three distinct sight openings 15, 16 and 17 respectively. These may serve to display card 18 as shown in Fig. 2. The bottom bar 12 is provided with a finger notch 19. The top bar is provided with a 50 downwardly bent lip 20 for receiving the lat-

erally bent upper end portions 21 on the arms 22 of the retainer 10.

The retainer includes a rectangular part 23 which surrounds the sight 17. The lower portion of this part 23 is formed with a substantially U-shaped finger grip 24 bent outwardly to protrude slightly through the notch 19 when the retainer is in the expanded clamping position shown in Figs. 1 and 2.

The upper end portions of the arms just 60 below the terminals 21 are secured to a retaining bracket 25 held in place by a screw or the like 26. This therefore positions the rectangular part 23 in a position to surround the opening 17 and to permit the arms 22 to 65 span the central portions of the areas 15 and 16.

Thus, one or more cards may be clamped between the device and the frame 5 in the manner as shown in Fig. 2. By placing the 70 thumb in the notch 19 against the finger grip 24 and pushing the device 10 inwardly, said device may be snapped behind the keepers 9 so that it is held in the position represented in Fig. 3 to permit easy insertion of 75 the card.

This device, it is understood, is attached to railway cars in lieu of the wood blocks now generally employed on steel freight cars for fastening cards thereto. The holder however, is equally adapted for use on wooden cars to avoid tacking of cards to the sides of the cars. The device eliminates the necessity of hammer and tacks in applying cards, thus making the cards easier to apply 85 and remove. It prevents mutilation of the cards.

It is far more dependable and neater than the present means for mounting cards. It will accommodate a variety of sizes and shapes of car cards and hold them securely and prevent their mutilation in attaching and removing. Little if any of the reading matter on the card will be obscured by the open work design of the frame.

It is to be understood that by describing in detail herein any particular form, structure or arrangement, it is not intended to limit the invention beyond the terms of the 100

several claims or the requirements of the prior art.

Having thus described my invention what I claim as new is:—

- 5 1. A card holder of the class described comprising a frame adapted to be rigidly mounted on a support, said frame comprising a substantially rectangular body including top and bottom bar members, a pair of spaced intermediate bar members, and longitudinal members connecting said bar members together to form a portion including a series of independent sight openings, said frame also including a pair of spaced parallel longitudinal side walls extending at right angles to said longitudinal members and defining a passage for reception of the card and adapted to bear against the support, said side walls being provided with attaching means, and a card retainer secured at its upper end to the corresponding end portion of said frame and including a substantially rectangular portion at its bottom surrounding the lowermost sight opening, and a pair of upstanding spaced arms spanning the remaining sight openings.

2. A card holder comprising a frame including an open work front portion, the lower end of which is provided with a finger notch, said frame also including spaced parallel side walls having inwardly pressed portions functioning as keepers, a resilient retainer disposed against the inner side of said front portion and having a finger grip depending below said finger notch, said retainer including portions detachably engageable with said keepers, whereby to permit the retainer to be swung inwardly and disposed temporarily in an out-of-the way position to facilitate insertion and removal of the card between the retainer and said frame.

3. A card holder comprising an openwork frame and a resilient wire retainer, said frame being provided adjacent its top and on its inner side with a depending apertured lip, a resilient wire retainer disposed against the inner surface of said frame and including a pair of arms having laterally directed terminals located in the apertures in said lip, and a fastener secured to said frame and including a bracket bridging the terminal end portions of said arms to aid in holding said retainer in position on the frame.

4. As a new product of manufacture, a frame for use in association with a card holder of the class described comprising a substantially rectangular body of sheet material including a frontal portion embodying a pair of longitudinal members, upper and lower end members, and a pair of spaced intermediate members all connected together and defining a series of three distinguishable sight openings, a pair of spaced parallel lateral side walls having their lower end portions formed with inwardly projected portions defining keepers, said side walls being provided

with outstanding apertured attaching ears, the aforesaid lower member being provided with a finger notch, and the intermediate portion of said upper member being provided with a depending apertured anchorage lip, a wire retainer confined in said frame and including a rectangular lower end portion and a pair of spaced parallel attaching arms having lateral terminals defining anchoring fingers secured in said lip, and a removable bracket fastened to said upper member at a point just beneath said lip and engaging adjacent portions of said arms.

In testimony whereof I affix my signature.

AUBREY H. TABOR.
